CARD STENCILING MACHINE WITH
ADDRESS PRINTING MEANS

Alexander D'Amato, Abington, Mass.

Application March 4, 1946, Serial No. 651,828

5 Claims. (Cl. 101—49)

1

This invention relates to apparatus for forming ink patterns of any kind, such as letters, figures, lines and the like, on both sides of a series of cards, such patterns being formed by stenciling, printing or other system of ink transfer. More particularly, the invention relates to a machine for stenciling an ink pattern, such as an advertisement, on one side of a series of cards, and stenciling on the other side of the cards successive names and addresses on successive cards, these stenciling operations on each card being done in rapid succession without inverting the card as it is fed through the machine.

To print a message and addresses on cards in prior machines of this general type, it is necessary to run the cards through the machine twice, the message being stencilled or printed on one side of the cards in the first run, the cards being addressed in the second run. In some machines of the prior art employing sector rolls for the stenciling operation, it is necessary to operate the machine intermittently, that is, with a brief dwell or pause after each stenciling operation to avoid premature engagement of the ink roll with succeeding cards or stencils.

According to the present invention, the apparatus is designed for continuous rapid operation without interruption, each card being fed continuously from a magazine at one end of the machine to a receptacle at the other end of the machine. During its passage through the machine each card is stencilled on its under face, a single stencil being used for this purpose. The upper face of the card is then stencilled with a name and address, a different stencil for each card being supplied from a magazine. Thus, one object of the invention is to provide a machine for rapid and continuous printing and addressing cards in a single run-through.

A further object of the invention is to provide a machine which will accommodate cards of different lengths and/or widths.

Other advantageous details and features of the machine will be apparent from the following description thereof, and from the drawings, of which:

Figure 1 is a side elevation of apparatus embodying the invention, part of the side wall being broken away to show interior parts;

Figure 2 is a partial plan view of the same;

Figure 3 is a section on the line 3—3 of Figure 1;

Figure 4 is a section on the line 4—4 of Figure 1;

Figure 5 is a section on the line 5—5 of Figure 1;

2

Figure 6 is a section on the line 6—6 of Figure 1;

Figure 7 is a fragmentary elevation of a pair of gears viewed as indicated by the line 7—7 of Figure 4;

Figure 8 is a partial sectional view of the machine taken on the line 8—8 of Figure 2, and shown on a larger scale.

The machine illustrated in Figure 1 comprises 10 a main frame 10 consisting of side walls, a bottom and a suitable number of transverse braces. Mounted on the main frame is an electric motor 12 connected by a shaft 14 to a gear box 16. As indicated in Figure 4, a drive shaft 18 is driven 15 at constant speed. This drive shaft is connected through change speed gearing, generally indicated at 20, to a shaft 22 in turn connected by a pinion and gear connection 24 to a second drive shaft 26. As hereinafter explained, parts of the 20 mechanism are driven from the constant speed shaft 18, other parts being driven from the changeable speed drive shaft 26. The gears can be conveniently shifted by means of a rod 27 having a handle 28 in an easily accessible position.

Mounted at one end of the main frame 10 is a receptacle or magazine 30 for cards. This magazine has a sloping floor 32 terminating in an opening 34 regulated by a gate which is adjustable by manipulation of an adjusting screw 36. Immediately below the opening 34 is a feed roll 38. An auxiliary roll 40 bears on the periphery of the wheel 38 to assist in the feeding of cards which are dislodged from the bottom of a stack 35 of cards within the magazine 30. In order to dislodge cards one by one from the bottom of the stack, a pair of friction elements 42 are mounted on the periphery of the feed roll 38. These elements are of suitable frictional material such as 40 rubber, the function of these elements being to start the bottom card of the stack toward the opening 34, the card being pushed into the nip of the rolls 38 and 40 which thereupon feed the card along a guide track 44 which has side flanges 45 as indicated in Figure 3. A second feed roll 48 is located beneath the guide track 44 and at a distance from the nip of the rolls 38 and 40 slightly less than the shortest card for which the machine is designed. The periphery of the feed 50 roll 38 projects up through an opening 50 in the track 44 so as to engage the under face of cards which are fed along the track. Upon the roll 48 is an auxiliary idle roll 52. When long cards are fed through the machine, the feed rolls 48 and 52 are unnecessary and the roll 52 may be 55 swung up out of action by a pivoted bracket 54.

by which it is supported, the roll being held in its elevated position by a latch 56 which engages the bracket 54. When the bracket 54 is released, a spring 58 presses the roll 52 against the roll 48 to insure proper feeding engagement with the cards which travel down the track 44.

The track 44 terminates at a point adjacent to an arcuate stencil holder 60 which is a part of a sector frame 62 including radial arms which are pivoted about the shaft 26 as indicated in Figure 4. The location of the sector frame on the shaft 26 is determined by a pair of adjustable collars 64 secured to the shaft 26. These parts of the frame 62 can be adjusted toward or from each other to accommodate stencils of different widths. Figure 4 shows a stencil 66 mounted on the stencil holder 60, the stencil being arcuate to conform to the shape of the holder. The holder 60 and stencil 66 thereon extend between a pair of rolls 70 and 72. The lower roll 70 is mounted on a shaft 74 which is driven as hereinafter described. The upper roll 72 is mounted on a stub shaft 76 journaled in a bracket 78 which is vertically slidable on a side wall of the main frame 10. The shafts 74 and 76 are connected for synchronous operation by a pair of gears 80 and 82. As indicated in Figure 7 these gears have elongated teeth so as to remain in mesh when the bracket 78 is elevated. A rod 84 projects down from the bracket 78 and terminates in a cam follower 86 which rides on a cam 88 mounted on the shaft 26. A spring 90 may be employed to augment the weight of the bracket 78 and roll 72 in holding the cam follower 86 against its cam 88. As is evident from the shape of the cam 88 indicated in Figure 8, rotation of the shaft 26 results in an alternate raising and lowering of the roll 72 so that for approximately half of each revolution of shaft 26 the upper roll 72 is pressed down against the roll 70, the roll 72 being lifted clear during the remaining half of each revolution of the shaft 26.

When the roll 72 is pressed into engagement with the roll 70, the stencil 66 and card from the magazine are caught between the rolls and are caused thereby to advance together, the frame 62 being consequently rocked about its axis. These rolls thus act as feed rolls but they also print as they feed. For this purpose the roll 70 is suitably inked by means of a transfer roll 92 which is supported by a pair of arms 94 pivoted about a shaft 96 so that the roll 92 can readily be swung out for access and cleaning. The roll 92 is also in contact with an ink feed roll 98 which is carried by the arms 94 and which is preferably oscillated in an axial direction during the operation of the machine by customary means, not indicated, for a more effective distribution of ink. The arms 94 also have suitable brackets 100 to support an ink fountain (not shown). When a card is fed down the track 44 to the rolls 70 and 72, the cam 88 reaches a point where it permits the roll 72 to descend and start feeding the card and stencil. As the card and stencil are advanced, the inked roll 70 prints an ink pattern on the under face of the card through the stencil 66. At the end of this feeding operation the cam 88 elevates the roll 72, releasing the card and stencil. The card by this time has reached the next feeding point and is carried along, but the stencil is retracted by a spring 102 which is attached to the frame 62 and which rocks the frame back to its initial position against a suitable stop 104.

When a card has been fed through the rolls 70 and 72, its forward end is picked up by a guid-

ing table 106 having a pair of upstanding flanges 108, these flanges being laterally adjustable to accommodate cards of different widths. An upper guide 110 is provided to prevent a card from curling upward away from the table 106. A driven feed roll 112 projects up through an aperture 114 in the table 106 so as to engage the under face of the card and feed the card forward. An auxiliary idle roll 116 is supported above the roll 112 by a yoke 118 carried by a leaf spring 120 which causes the auxiliary roll 116 to bear resiliently against the roll 112. Hinged to the yoke 118 is a horizontal plate 122 which bears on cards as they are fed along the upper face of the table 106 and thus keeps them flat as they approach the next feeding point.

Above the table 106 is a stencil magazine 124 adapted to contain a stack of address stencils. In order to eject these stencils one by one from the bottom of the stack a pusher 126 is provided, this pusher being in the form of a sliding plate, as indicated in Figure 2, and having an upstanding lug 128 which engages the end edge of the bottom stencil 130 in the stack and pushes it forward to overlie a card that is fed along the table 106 beneath as indicated in Figure 8. The pusher 126 is reciprocated by any suitable means such as a connecting rod 132 attached to a crank 134 mounted on a shaft 136, this shaft being driven through gears 138 and 140 from a shaft 142.

The stencils 130 are guided by a suitable track 144 which extends, as indicated in Figures 1 and 6, to a suitable receptacle 146 at the end of the machine. The stencils push each other along until they drop into the receptacle 146 where they are collected.

Mounted on the shaft 142 is a roll 148 which projects up through the guide table 106 to feed the cards and their address stencils, which come from the feed roll 112 and magazine 124 respectively. Cooperating with the roll 148 is an upper roll 150 mounted on a vertically movable bracket 152, the bracket having a rod 154 projecting down therefrom and terminating in a cam follower 156 which rides on the edge of a cam 158, the cam being mounted on a shaft 160 (Figures 1 and 8). The rolls 148 and 150 are connected by gears 162 indicated in Figure 2, these gears being preferably similar to the gears 80 and 82 shown in Figure 7 so that they remain in mesh even when the bracket 152 which carries the roll 150 is raised. If desired, a spring 164 may be employed to press the follower 156 against its cam 158. The cam 158 is shaped so as to permit the roll 150 to be in its lower position against the roll 148 for a limited period during which a card and a stencil thereon is fed a limited distance by the rolls 148 and 150. The roll 150 is then elevated by the cam 158 until the next card and stencil come into position. The roll 150 in addition to being a feed roll is also an inking roll, ink being supplied from a transfer roll 166 which is mounted on an arm 168 pivoted at 170 on a bracket 172. The transfer roll 166 receives ink from an ink feed roll 174 which in turn receives ink from a fountain (not shown) supported by a suitable bracket 176. The feed roll 174 and bracket 176 are mounted on the arm 168 so that the train of ink rolls can be swung back out of the way for access to the roll 150. The pivoted arm 168 also permits uninterrupted contact between the rolls 150 and 166 when the roll 150 is raised and lowered.

When a card has passed the rolls 148 and 150, it slides down an inclined guide-way 180 into a suitable receptacle 182 in the machine frame.

As indicated in Figure 1, the constantly rotating drive shaft 18 drives the roll 70 and the roll 112 at constant speed through suitable sprocket wheels and a connecting chain 134. The drive shaft 26, the speed of which can be changed by means of the change-speed gears 20, drives the first and second feed rolls 38 and 48, the press roll 148 and the shaft 160 by means of suitable sprocket wheels and a connecting chain 186. The feed rolls 38 and 48 are thus synchronized in their operation with the cams 88 and 158, the latter being mounted respectively on the shafts 26 and 160. The purpose of the change-speed gearing 20 is to enable the machine to accommodate cards of different lengths. For example, the machine illustrated by the drawings is constructed to print cards of postcard length, that is, 5½ inches, or cards which are 8¾ inches in length, but the machine can easily be adjusted to print cards of other lengths. When the shorter cards are printed, the shaft 26 and the other shafts connected therewith are operated at a greater speed than when the longer cards are put through the machine. Since the drive rolls 70 and 72 which operate the first stencil 66 are driven at constant speed, a faster operation of the cam 88 will result in an operation of these drive rolls for shorter intervals than when the cam is revolved at a lower speed. In the former case, the stencil holder 60 has time to be fed through the rolls 70 and 72 for only a part of its length, this part corresponding to the length of one of the shorter cards. When the longer cards are employed, the cam 88 is revolved more slowly and thus enables the rolls to operate for longer time intervals, that is, for a sufficient time to feed the stencil holder 60 through a length equal to one of the longer cards. When the speed of rotation of the cam 88 is changed to accommodate a card of different length, the speed of the cam 160 is also changed accordingly so that these two cams may always be kept in step.

What I claim is:

1. Apparatus of the class described comprising a main frame, a rocking frame supported by said main frame and rockable about a horizontal axis, said rocking frame including an arcuate stencil holder concentric with said axis, a stencil secured to said holder, a pair of rolls rotatable about horizontal axes which are in a common vertical plane with said rocking frame axis, means for driving said rolls, said stencil extending between said rolls so as to be advanced thereby when the rolls are pressed together, means for driving said rolls, means for alternately moving one said roll to and away from the other roll to advance and to release said stencil alternately, and yielding means for retracting said stencil and holder when the stencil is released.

2. Apparatus of the class described comprising a main frame, a magazine mounted on said frame, means for feeding successive cards from said magazine, a rocking frame rockable on said main frame about a horizontal axis, an arcuate stencil carried by said rocking frame concentric with said rocking axis, means for guiding cards fed from said magazine onto said stencil, a pair of rolls carried by said main frame adjacent to the end of said guide means and respectively above and below said stencil, means for driving said rolls at a constant speed, means for moving one said roll bodily alternately to and from engagement with the other roll to grip said stencil.

and a card between the rolls whereby said stencil and card are advanced through a printing stroke and then released, means for inking the lower of said rolls, spring means for returning the released stencil to its initial position, means for continuing the advance of the card after its release from said rolls, and means for driving said card feeding means and cam means in timed relation.

3. Apparatus of the class described comprising a main frame, a magazine mounted on said frame, means for feeding successive cards from said magazine, a rocking frame rockable on said main frame about a horizontal axis, an arcuate stencil carried by said rocking frame concentric with said rocking axis, means for guiding cards fed from said magazine into engagement with said stencil, a pair of rolls carried by said main frame adjacent to the end of said guide means and respectively above and below said stencil, means for driving said rolls at a constant speed, means for moving one said roll bodily alternately to and from engagement with the other roll to grip said stencil and a card between the rolls whereby said stencil and card are advanced through a printing stroke and then released, means for inking the lower of said rolls, spring means for returning the released stencil to its initial position, means for driving said card feeding means and cam means in timed relation, and means for changing the speed of the last mentioned driving means relative to the speed of said roll drive to accommodate cards of different lengths.

4. Apparatus of the class described comprising a frame, a card magazine, means for feeding cards in succession from said magazine, a reciprocable stencil, means for guiding cards from said feeding means to said stencil, a pair of rolls mounted on said frame with said stencil extending between them, means for driving said rolls at a constant speed, spring means pressing said rolls together to advance said stencil and card thereon, cam means for intermittently separating said rolls to release said stencil and card, spring means for restoring the released stencil to its initial position, a stencil magazine on said frame, means for feeding cards released by said rolls to pass beneath said stencil magazine, means for feeding address stencils one by one from said magazine as said cards pass under the stencil magazine, a second pair of rolls adapted to receive address stencils and cards between them, means for driving said press rolls, spring means pressing said press rolls together, cam means intermittently separating said press rolls, means for driving said card feeding means, said stencil feeding means and both said cam means in timed relation, and means adjustable to change the speed of said driving means relative to the speed of the first said roll drive to accommodate cards of different lengths.

5. Apparatus of the class described, comprising a frame, a reciprocable stencil holder supported by said frame, spring means yieldingly maintaining the holder in a predetermined initial position, a stencil in said holder, a pair of rolls on said frame having said stencil extending between them, means for continuously driving said rolls, means for inking one of said rolls, means for alternately pressing said rolls together and separating said rolls whereby said stencil is advanced by said rolls from its initial position when said rolls are pressed together and is returned to said initial position by said spring means.

when the rolls are moved apart, and means synchronized with the movements of the rolls to feed a card onto said stencil at the beginning of each movement thereof from said initial position.
